UNITED STATES PATENT OFFICE.

EUGENE A. SIMONS, OF MARCUS, IOWA.

OPERATING TABLE.

Application filed July 29, 1926. Serial No. 125,663.

My invention relates to folding tables, particularly adapted for use in veterinary operations. It is my object to provide a table of such shape that a pig or other animal may be securely held on the table with little effort.

More particularly, it is my object to provide a table having a trough or V-shaped top between the sides of which the animal may be placed in inverted position.

A further object is to provide legs for supporting the table, the legs being foldable against the sides of the top members of the table to form a compact package.

Another object is to provide a strap in connection with the top, for holding the nose of an animal, said strap serving also to hold the legs in folded position if desired.

A still further object of my invention is to provide legs so arranged that when in supporting position a pair of crossed legs secured to one member of the top cross a pair of crossed legs secured to the other member of the top in such a manner that a chain may be secured between the pairs of legs at their individual crossing points and serve to regulate the distance between the pairs of legs and consequently the height of the table.

A further object is to provide a hinge connection between the individual legs of each pair of legs which will allow them to fold to most compact position against the top members.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Fig. 1 is an end elevation of the table in operative position.

Fig. 2 is a side elevation of the same.

Fig. 3 is a plan view of the same.

Fig. 4 is a perspective view of a leg hook.

Fig. 5 is a detail view of the leg hinge.

Fig. 6 is a view illustrating one stage of folding the legs of the table.

Fig. 7 is a view illustrating a further stage of folding, the last stage being shown in dotted lines.

Fig. 8 is an end view of the table folded.

I have used the reference character 10 to illustrate a side member of the top, formed of a plank of suitable proportions. There

are two members 10 connected by hinges 11.

I provide two pairs of legs which I will designate by the reference characters A and B. Each pair comprises a leg 12, pivoted to its respective top member 10 by means of a bolt 13, and a leg 14, removably secured to its respective top member by means of a hook 15, secured to the leg 14, and having a bifurcated portion 16. (Fig. 4).

The ends of the bifurcated portion 16 are bent inwardly as at 17. A stud 18 is secured in the top member 10 in position to be received by the bifurcated portion 16, and a nut 19 is threaded onto the stud 18 to secure the hook 15. In order to remove the hook from the stud, the nut must be threaded away from the bifurcated portion 16 sufficiently to clear the hooked ends 17.

Each pair of legs is crossed and secured together, by means of a hinge as shown in Fig. 5. The hinge is of an ordinary variety, having the two leaves 20 and 21. The leaf 20 is secured to the leg 14 and the leaf 21 is pivoted by means of a bolt 22 to the leg 12. The pivot 22 allows the leg 14 to swing from the position shown in Figs. 1 to 3, and in dotted lines in Fig. 6, in the common plane of the legs, of the particular pair, to the position shown in full lines in Fig. 6. The pivot 23 then allows the leg 14 to hinge about the leg 12 to the position shown in full lines in Fig. 7. From thence the two legs may be swung to the position shown in dotted lines in Fig. 7 and in full lines in Fig. 8.

The legs of the pair B embrace the legs of the pair A, and in collapsing the table, the pair B is first folded.

In order to do this, the leg 14 is first unhooked from its top member, is swung to the position shown in full lines in Fig. 6, and the pair of legs then swung to a position substantially perpendicular to the lower edge of the top member, in order to clear the end of the leg 14 of the pair A. The top members are then collapsed together, uncrossing the two pairs of legs. The respective pairs may then be folded as previously described, to the positions shown in Fig. 8.

Without the hinge pivot 23, the legs could still be collapsed, against the sides of the top members, but would stand out one upon another away from the member. The pivot 22 allows the bringing of the legs of a pair together in parallel, side by side relation.

I provide a strap 25, received through slots 26 in the top members 10.

In using the table, the height is adjusted by moving the pairs of legs toward or from each other, and they are then secured by a chain 27 linked between them as shown. By shortening the chain, the height of the table will be raised, as will readily be seen.

In working on large animals, it is desirable to have the table lower, to facilitate handling the animal, and the top members are correspondingly spread at a greater angle to accommodate the wider back of the animal. For small animals, the work may be more easily performed with the table at a greater height, and the top members are correspondingly brought closer together by raising the top, to more securely receive the narrower back of the animal.

20 The animal is placed on its back in the trough as indicated by dotted lines in Fig. 1. The strap 25 is then placed over the jowl of the animal, the hind leg held by one person and the hypodermic needle or knife handled by another. Ordinarily several men are required just to hold the animal. With my device the animal may be held with ease by one man and held in such a way that he cannot move.

30 The strap 25 may be employed as indicated in Fig. 8, if desired, to secure the legs in folded positions.

By extending the ends of the legs 12 beyond the pivots 13 as shown in Fig. 2, the top members are braced against spreading.

It will be seen that the greater the weight upon the table, the more firmly braced will the legs become.

40 Some changes may be made in the construction and arrangement of the parts of my invention, without departing from the real spirit and purpose of my invention, and it is my intention to cover by my claims, any modified forms of structure or use of mechanical equivalents, which may be reasonably included within their scope.

I claim as my invention:

1. In an operating table, two top members hinged together to form a trough, a pair of legs secured to each member and secured together in crossed relation, the respective pairs crossing each other above the points where the legs of those pairs are secured together and a flexible element extending between the pairs and looped around the pairs where the legs of those pairs cross each other, said flexible element being secured upon itself at one of several possible positions along its length to thereby form a loop of variable dimensions for tying the pairs together against outward pressure caused therebetween by downward pressure upon the trough.

60 2. In an operating table, two top members hinged together to form a trough, a pair

of legs pivotally secured to each member and pivoted together in crossed relation, the respective pairs crossing each other above the points where their legs are pivoted together and adjustable means connecting the pairs and positioned between their pivot points whereby downward pressure imposed between the members of the trough will rigidify the legs in their relation to each other and the trough.

70 3. In an operating table, a pair of top members hinged together to form a trough, a pair of crossed legs secured to each member, the legs of each pair being pivoted together on an axis perpendicular to the legs, hooks secured to the upper end of one of the legs of each pair, studs secured to the top members and received by said hooks and nuts threaded onto the studs to secure the hooks thereto.

80 4. In an operating table, a pair of top members hinged together to form a trough, a pair of crossed legs secured to each member, the legs of each pair being pivoted together on an axis perpendicular to the legs, hooks secured to the upper end of one of the legs of each pair, studs secured to the top members and received by said hooks and nuts threaded onto the studs to secure the hooks, the hooks having inwardly bent portions to lock them against removal from the studs when the nuts are threaded down against the hooks.

90 5. In an operating table, a pair of top members hinged together to form a trough, a pair of crossed legs secured to each member, the legs of each pair being pivoted together on an axis perpendicular to the legs, a hinge allowing the legs to move on a second axis parallel to the legs, said hinge being secured to one of the legs and pivoted to the other leg to provide said pivotal connection therebetween, one of the legs of each pair being detachable from its top member to allow folding of the pair of legs side by side against the top member.

100 6. In an operating table, a pair of top members hinged together to form a trough, a pair of crossed legs secured to each member, the legs of each pair being pivoted together where they cross, on an axis perpendicular to the legs, one of the legs of each pair being detachable from its top member to allow folding of the pair of legs side by side against the top member.

110 7. In an operating table, a pair of top members hinged together to form a trough, a pair of crossed legs secured to each member, the legs of each pair being pivoted together on an axis perpendicular to and on a second axis parallel to, the legs, one of the legs of each pair being detachable from its top member to allow folding of the pair of legs side by side against the top member.

EUGENE A. SIMONS.
